UNITED STATES PATENT OFFICE.

JOSEPH H. TRAVIS, OF CHARLESTOWN, AND EUGENE H. MAHONEY, OF BOSTON, MASSACHUSETTS.

DESIGN FOR SIDE FRAMES FOR CHAIRS.

Specification forming part of Design No. 5,559, dated February 27, 1872.

To all persons to whom these presents shall come:

Be it known that we, JOSEPH H. TRAVIS, of Charlestown, in the county of Middlesex and State of Massachusetts, and EUGENE H. MAHONEY, of Boston, in the county of Suffolk and State aforesaid, have invented a new and Improved Design for Side Frames to Chairs; and that the following description, taken in connection with the accompanying drawing, is a full and exact specification of the same.

The design embraced in this invention consists of a side frame for chairs having backs.

The invention is shown in the accompanying drawing, of which the figure is a perspective view of a chair, the side frame of which is designed according thereto.

A in the drawing represents the side frame of the chair. This side frame consists of parts B, C, and D, the part B receiving the back, the part C the seat, and the part D being the legs—one at the front and one at the rear. The part B in its length is at a backward in-

clination to the part C, and at E, where it meets the part C, it is in its front edge curved or concaved, as shown, the part C from thence continuing in a curved line, F, to or nearly to plane of junction of the legs with it. The part D, or the legs, are in their length of a more or less curvular form, and are at an angle to the part C, and as they proceed therefrom extend or spread out from each other.

Having thus described our new design, we shall state our claim as follows:

The design for a side-frame to a chair, substantially as herein described.

The above specification of our improved design for side-frames to chairs signed by us this 1st day of February, A. D. 1872.

J. H. TRAVIS.
E. H. MAHONEY.
